UNITED STATES PATENT OFFICE.

WILLIAM CLIFTON CUTLER, OF SAWTELLE, CALIFORNIA.

DISPLAY-MACHINE.

1,111,725.

Specification of Letters Patent. Patented Sept. 22, 1914.

Application filed July 10, 1913. Serial No. 778,332.

To all whom it may concern:

Be it known that I, WILLIAM C. CUTLER, a citizen of the United States, residing at Sawtelle, in the county of Los Angeles and State of California, have invented a new and useful Display-Machine, of which the following is a specification.

This invention relates to display machines and particularly to a machine for displaying directory matter.

One of the objects of the invention is to provide a display machine in which the subject matter to be displayed may be classified alphabetically, numerically or otherwise, and having an index provided with characters corresponding to the classification characters of the subject matter, so that the operator upon selecting by said index the character corresponding to the character under which the information he desires is classified, may have such information displayed before him.

Another object of the invention is to provide a display machine having a platform connected with the display mechanism of the machine, upon which the operator is adapted to stand and depress the platform by his weight, which platform is adapted when depressed to actuate the display mechanism.

A further object of the invention is to provide an index for the machine by means of which the operator may select from the subject matter which the machine is adapted to display, the particular information which he desires to have displayed to him.

Other objects will appear from the following description.

A desirable embodiment of my invention is illustrated in the accompanying drawings in which:

Figure 1 is a perspective view showing the cabinet in which the mechanism of the machine is mounted, the index and the platform mechanism for actuating the display mechanism of the machine, the lower portion of the cabinet being broken away, and the platform removed to show the platform mechanism. Fig. 2 is a plan view of the index and selecting mechanism and its connection with the display mechanism of the machine. Fig. 3 is a cross sectional view of the index and selecting mechanism taken on line x^1-x^3 of Fig. 3. Fig. 4 is a left side elevation of the display mechanism of

the machine. Fig. 5 is a front elevation of the display mechanism. Fig. 6 is a right side elevation, partly broken away, of the display mechanism and associated parts. Fig. 7 is a perspective view illustrating certain features of the card lifting and lowering means of the display mechanism.

The mechanism of the machine is mounted in a cabinet 1, in the base of which is an extension 2 above which is mounted the platform 3. An opening 4 which is covered by a glass panel 37 is located in the front wall of the cabinet near the top thereof, on a level with the eye of a person of ordinary height, while standing upon the platform 3. In the upper portion of the cabinet is located the display mechanism A. A frame 5 supports the various elements of the display mechanism which will now be described. A jiffy curtain 6 is wound upon the roller 7 journaled in the frame 5, and is adapted to slide in grooves 50 of guides 51 on said frame between the glass paneled opening 4 and the display cards to be described hereinafter, a weight 6' is attached to the free end of the curtain to drop the curtain.

Mounted upon shaft 52 journaled in the upper part of the frame 5 below the roll 7 is a pair of sheaves 24 to each of which is secured one end of a cord 53 which cords are adapted to wind upon or unwind from the sheaves according to the direction of rotation of the sheaves. The sheaves are located adjacent the guides 51 on the sides of the frame 5 and the lower ends of the cords 53 are connected to the card coupling element 26 at the ends of said element which ends slide in grooves 54 in the guides 51.

The exhibits, consisting of cards C upon which is placed the information which is displayed to the operator, are contained in a case 12 mounted upon a carriage 60 which travels in tracks 61 on the frame 5. A rack 62 secured to the carriage 60 meshes with a pinion 63 journaled in the frame 5, which in turn meshes with pinion 64 on shaft 65, the lower end of which is journaled in the frame.

An index I and selector S by means of which the desired information to be displayed is selected will now be described.

Mounted upon the upper end of the shaft 65 is an index disk 66 which rests upon a dial 67 and is journaled in a bearing 68 on

- said dial. An oscillative disk 15 is mounted upon the dial bearing 68 and rests upon and is maintained on said bearing against the lower face of said dial by means of a stationary disk 70 secured to the bearing 68 by screw 71. An index plunger 75 is mounted upon the index disk 66 in a bearing 18 and is provided with an actuating button 11 by means of which the plunger is depressed in the manner and for the purposes more fully described hereinafter. An opening 76 is provided in the disk 66 through which the plunger 75 is depressed. A spring 77 rests between the button 11 and bearing 18 which spring normally maintains the lower end of the plunger above the lower face of the disk 66. The dial 67 and stationary disk 70 are provided with a plurality of holes 78 and 79 respectively, each 29 of the holes 78 registering with a hole 79. The oscillative disk 15 is also provided with a plurality of holes 80 which normally rest slightly out of registration with the holes 78 and 79 of the dial and stationary disk. 25 The location of the hole 76 in the index disk is such that it may be brought into registration with the holes 78 and 79 in the dial and stationary disk so that the plunger 75 may be depressed into said holes. The 30 lower end 75^a of the plunger is tapered so that it will enter the holes 80 in the oscillative disk when the plunger is depressed. Upon entering a hole 80 in said disk the tapered end of the plunger 75 acts as a cam 35 against the edge of the hole and causes the oscillative disk to oscillate until the holes 80 are brought into registration with the holes 78 and 79 in the dial and stationary disk. The oscillative disk is provided with 40 an arm 38 adapted to engage a bar 19 in the manner and for the purpose hereinafter described.
- The upper face of the dial 67 is provided with a set of characters, such as letters, numbers or other indicia which correspond to a set of characters under which the displaying cards C are classified. The characters on the dial are so located that when the index plunger 75 is brought opposite one of said 45 characters it will register with one of the holes 78 and one of the holes 79 in the dial and stationary disk respectively. The index plunger, index disk and dial above described are located outside the cabinet 1 upon a shelf 85 on the cabinet in a convenient place for the operator while standing upon the platform 3, while the mechanism associated with said index parts is inclosed within the cabinet.
- 50 Pinions 31 and 90, mounted respectively on the curtain roll shaft 7^a and sheave shaft 52, are respectively engaged by racks 91 and 92 mounted upon the frame 5 whereby the curtain roll 7 and sheaves 24 are respectively 55 rotated to raise the curtain 6 and the display cards C as hereinafter more fully described. Springs 10 and 25 surround the lower portions of the rack bars 93 and 94 and are maintained on said bars by collars 95 secured to the lower ends of said bars. A yoke 96, 70 which surrounds the bars 93 and 94 and rests upon the upper ends of the springs 10 and 25, is connected to one end of a lever 97 by link 98, the other end of which lever is fulcrumed upon the frame 5 at 100. An elongated link 36 connects the lever 97 with one arm of bell crank lever 9 mounted upon rod 101 journaled in the lower portion of the cabinet 1. A link 102 connects the other arm of bell crank lever 9 to the arm 103 of 80 one of a pair of bell crank levers 104 mounted upon rod 105 journaled in the extension 2 of the cabinet 1. A link 106 connects the arm 103 of the other bell crank lever 104 to the arm 107 of bell crank lever 108 mounted 85 upon rod 109 journaled in the cabinet extension 2. The arm 110 of bell crank lever 108 is connected to one end of bar 111, the other end of which is connected to arm 112 also mounted upon shaft 109. A bar 113 90 similar to bar 111 is connected at its respective ends to the arms 114 of bell crank levers 104. The platform 3 is mounted upon the bars 111 and 113.
- The yoke 96 is connected to a rod 115 95 which extends through brackets 116 and is surrounded by a spring 117 between the yoke and lower bracket which spring normally maintains the yoke in its uppermost position, as shown in Fig. 4. In this position of the yoke the spring 117 maintains the platform 3 through its connections with the yoke, in its uppermost position. Moreover, when the yoke is in its uppermost position the springs 10 and 25 are expanded 100 and the curtain 6 and display card coupling element 26 are lowered.
- A ratchet 120 on shaft 52 is adapted to be engaged by a pawl 23 pivoted upon a short shaft 22 journaled in the frame 110 5 to lock the shaft 52 and sheaves 24 against rotation, during which condition the coupling element 26 is maintained in its lowermost position. An arm 121 is secured 115 on the shaft 22 and is connected by link 21 to one arm 122 of bell crank lever 20 fulcrumed upon frame 5 at 123, the other arm 124 of said bell crank lever being connected to the sliding bar 19 slidably mounted in a guide 125 on the frame, which bar is adapted 120 to be engaged by the arm 38 of the oscillative disk 15, when said disk is oscillated by the index plunger 75, to disengage the pawl 23 from the ratchet 120 through the above described connections between said 125 bar and said pawl.
- A spring 126 acting upon the bar 19 normally maintains the pawl 23 in engagement with the ratchet 120, and the oscillative disk in the position shown in Fig. 2 of the draw- 130

ing, with the holes 80 therein out of registration with the holes 78 and 79 of the dial 67 and disk 70 respectively.

A ratchet 131 mounted upon curtain roll shaft 7^a is engaged by pawl 29 mounted upon short shaft 132 journaled in frame 5, normally to lock the curtain in its lowered position, in which position the curtain covers the opening 4 to hide the display mechanism from view through said opening, while said mechanism is in its non-displaying position. An arm 28 is also mounted upon shaft 132 which arm is adapted to be engaged by cam 27, mounted upon shaft 52 when a display card C has been elevated into registration with opening 4 in its displaying position, to disengage said pawl from said ratchet to allow the curtain 6 to be elevated by the roll 7 to expose the card 20 to the operator through the opening 4. A spring 133 normally maintains the pawl 29 in engagement with the ratchet 131.

A ratchet 35 mounted upon shaft 52 is engaged by pawl 33 mounted upon short shaft 135, journaled in frame 5, when the card C has been elevated into displaying position, to lock the card in such position until the operator obtains the information which he desires and steps off the platform 3 and the curtain 6 drops by gravity and covers the opening 4 in cabinet 1. An arm 32 secured to shaft 135 is engaged by cam 34 on curtain shaft 7^a to disengage the pawl 33 from ratchet 35 to allow the card to drop by gravity into the case 12, after the curtain has dropped and covered the opening 4. The pawl 33 is maintained in engagement with ratchet 35 by spring 137.

A stop 140 on the frame 5 is engaged by a pin 141 on the curtain roll 7 whereby the winding motion of the curtain roll is arrested when the curtain is wound sufficiently to uncover the opening 4 in the cabinet 1.

A pin on one of the sheaves 24 engages a pin 151 on the frame 5 to arrest the rotation of the sheaves 24 when the card C has been elevated into register with the cabinet opening 4 or lowered into the case 12.

The card coupling element 26 is provided with a pair of lugs 13 which engage the hooks 39 on the cards C whereby a card is coupled to the cords 53 so that the card may be elevated into displaying position upon rotation of shaft 52 and sheaves 24 in one direction or lowered out of displaying position into the case 12, upon rotation of said shaft and sheaves in the other direction.

The operation of my invention is as follows: Assume the display mechanism of the machine to be in its non-displaying position and the platform 3 in its uppermost position as shown in Fig. 1 of the drawing. If the operator desires certain information classified for example under the letter A, he first stands on the platform 3 and his

weight depresses the platform and draws down the yoke 96 against the tension of the springs 117, 10 and 25 and thereby compresses these springs. The operator then grasps the button 11, turns the index disk 70 66 until the plunger 75 is opposite the letter A on the dial 67 and in registration with the hole 78 in the dial opposite said letter, during which movement of the index disk, the shaft 65 is rotated and the carriage 69 75 through the medium of gears 64 and 63, and rack 62 is moved along the track 61 until the card marked A which is contained in the carriage case 12 is brought into registration with the card coupling element 26 and with the card hooks 39 in engagement with the lugs 13 of said coupling element. The operator then presses down upon the button 11 thereby depressing the plunger 75 into the apertures 80 and 79 in the oscillative disk 15 and stationary disk 70 respectively and as the lower tapered end of the plunger enters the hole 80 in the oscillative disk it causes said disk to oscillate until the hole 80 registers with holes 78 and 79 in the dial 67 and disk 70. As the disk 15 is oscillated, the arm 38 thereof engages the bar 19, draws said bar forward against the tension of spring 126, and as the bar is drawn forward it rocks the bell crank lever 20 which in turn rocks shaft 22 through rod 21 and arm 121 and disengages the pawl 23 from ratchet 120. As soon as the pawl 23 disengages the ratchet 120 the spring 25 expands and draws down the rack 91 which rotates the shaft 52 and sheaves 24, through the medium of pinions 90, in the direction of the arrow in Fig. 4 until pin 150 engages pin 151 which arrests the rotation of the shaft 52 and sheaves 24. As said shaft and sheaves are thus rotated, the cords 53 are wound around said sheaves whereby the card marked A through the medium of coupling element 26 is elevated into registration with opening 4 in the cabinet 1 behind the curtain 6 said card being prevented from being drawn above said opening out of registration therewith by the engagement of pin 150 and 151. Just as said shaft and sheaves complete their rotation the cam 110 27 engages the arm 28, rocks said arm and shaft 132 and thereby disengages the pawl 29 from the ratchet 131 and as said pawl 29 disengages said ratchet 131, the pawl 33 is drawn into engagement with the ratchet 24 120 on shaft 52 by means of spring 137. As soon as the curtain roll 7 is released by the disengagement of the pawl 29 from the ratchet 131, the spring 10 expands, draws down the rack 91, and through the medium 125 of the pinion 31 rotates the roll 7 and elevates the curtain above the opening 4 in the cabinet 1, thereby exposing to the operator through said opening, the card marked A, containing the information which the oper- 130

ator desires. When the card has been displayed, to the operator as long as he desires to see it, the operator steps off the platform 3, whereupon the spring 117 expands and elevates the yoke into its initial position and at the same time elevates the platform 3 into its initial position, as shown in Fig. 1, through the medium of the connections between the platform and the yoke. As the yoke 96 is elevated by spring 117, the springs 10 and 25 expand, and the force of said springs is removed from the bars 93 and 94 whereupon the curtain drops by gravity under the influence of weight 6, unwinding from the roll 7 in front of the card and shutting the card from view through the opening 4 in the cabinet. As the roll 7 is rotated by the dropping and unwinding of the curtain the pinion 31 is rotated and elevates the rack 91 and bar 93 to initial position, as shown in Fig 4. When the curtain has dropped and covered the opening 4, the cam 34 on roll shaft 7 engages the end of the arm 32 which in turn rocks shaft 135 and disengages the ratchet 35, whereupon the card C drops by gravity with the card coupling element 26 into the carriage case 12, at the same time rotating the sheaves 24, shaft 52 and pinion 90, and drawing up the rack 92 into its initial position, as shown in Fig. 4.

What I claim is:

1. In a displaying machine, an exhibit, an exhibit coupling element, cords connected to said element, sheaves around which said cords are wound to move said exhibit into displaying position, a shaft upon which the sheaves are mounted, a pinion on said shaft, a rack engaging said pinion, a spring for actuating said rack, platform mechanism adapted to compress said spring when the operator stands on the platform, means for locking said shaft against rotation, and means for releasing said shaft to enable said spring to expand to move the exhibit into displaying position through the medium of said rack, pinion, sheaves, shaft, cords and coupling element.
2. A displaying machine comprising a cabinet provided with a sight opening, a curtain for closing said opening, a roll upon which the curtain is wound, an exhibit adapted to be displayed through said opening, a pinion in connection with said curtain roll, a rack meshing with said pinion, means for reciprocating said rack to rotate said pinion and roll to wind up the curtain to display the exhibit through said sight opening.
3. A displaying machine comprising a cabinet provided with a sight opening, a curtain for closing said opening, a roll upon which the curtain is wound, an exhibit adapted to be displayed through said opening, a pinion in connection with said curtain

tain roll, a rack meshing with said pinion, a spring for actuating said rack, platform mechanism for compressing said spring, means for locking said curtain roll against rotation with the curtain covering said opening, means for releasing said roll to enable said spring to expand to actuate the rack to cause the pinion and roll to rotate and wind up the curtain to display said exhibit through said sight opening.

4. A displaying machine comprising a cabinet provided with a sight opening, a curtain for said opening, a roll upon which said curtain is wound, an exhibit, a shaft, sheaves mounted upon said shaft, cords connected to said sheaves, an exhibit coupling element connected to said cords for coupling the respective exhibits to said cords, a ratchet in connection with said curtain roll, a pawl engaging said ratchet to lock the curtain in position when covering said opening, an arm in connection with said pawl, a cam on said shaft means for rotating said shaft and sheaves to wind the cords on said sheaves to draw the exhibit coupled to said cords into registration with said opening and to cause said cam to engage said pawl arm, to disengage said pawl from said ratchet, means for winding up the curtain on said roll when released by the disengagement of said pawl from said ratchet to display the exhibit through said opening, a ratchet on said sheave shaft, a pawl adapted to engage said sheave ratchet when the exhibit has been drawn into registration with said sight opening, to lock the exhibit in displaying position, an arm in connection with said pawl, a cam in connection with said curtain roll, said curtain adapted to unwind from the roll and cover said opening, when the exhibit has been sufficiently displayed, said curtain roll cam adapted to engage said arm, when the curtain has closed said opening, to disengage the pawl from the sheave ratchet to enable the exhibit to move out of registration with said sight opening.

5. A displaying machine comprising a cabinet provided with a sight opening, a curtain for said opening, a roll upon which said curtain is wound, an exhibit, a shaft, sheaves mounted upon said shaft, cords connected to said sheaves, an exhibit coupling element for coupling the respective exhibits to said cords, means for rotating said shaft to wind the cords on the sheaves, to draw the exhibit coupled by said coupling element to said cords into registration with said opening, a ratchet on said sleeve shaft, a pawl for engaging said ratchet when the exhibit has been drawn into registration with said sight opening to lock the exhibit in displaying position, an arm in connection with said pawl, a cam in connection with said curtain roll, and means for winding up the curtain on said roll to uncover the opening and dis-

play the exhibit through said opening, said curtain adapted to unwind from the roll and cover said opening when the exhibit has been displayed, said cam adapted to engage 5 said arm when the curtain has closed said opening, to disengage the pawl from said ratchet to enable the exhibit to move out of registration with said sight opening.

6. In a displaying machine, a plurality of 10 exhibits, a dial provided with a plurality of holes, an oscillative disk provided with a plurality of holes, slightly out of registration with the dial holes, a selecting plunger rotatably mounted to turn upon said dial, 15 adapted to be rotated into registration with the dial hole in relation to the desired exhibit to shift said exhibits to bring the desired exhibit into engaging position, displaying means for engaging said exhibit,

means for locking said displaying means 20 until the desired exhibit has been selected by said plunger, said plunger having an engaging end, said plunger adapted to be depressed through said dial hole to cause said engaging end to engage the disk hole and 25 draw said hole into registration with the dial hole to oscillate the disk, means intermediate said disk and said locking means for unlocking said locking means from said displaying means, and means for actuating said 30 displaying means to display said exhibit.

In testimony whereof, I have hereunto set my hand at Los Angeles, California, this 12th day of April, 1913.

WILLIAM CLIFTON CUTLER.
